Patented Sept. 17, 1957

181,021

VEHICULAR TRACTION CLAMP

Irving Puhn, Douglaston, N. Y.

Application December 12, 1955, Serial No. 39,304

Term of patent 14 years

(Cl. D90—20)

FIG. 1.

FIG. 2.

FIG. 3.

Figure 1 is a perspective view of a vehicular traction clamp showing my new design;

Figure 2 is a bottom plan view thereof; and

Figure 3 is an end elevational view thereof.

I claim:

The ornamental design for a vehicular traction clamp, substantially as shown.
